(57) **CLAIM**

The ornamental design for a stand mixer, as shown and described.

DESCRIPTION

FIG. 1 is a top perspective view of the stand mixer in accordance with my new design;
 FIG. 2 is a top plan view thereof;
 FIG. 3 is a front elevational view thereof;
 FIG. 4 is a left-side elevational view thereof;
 FIG. 5 is a right-side elevational view thereof;
 FIG. 6 is a rear elevational view thereof; and,
 FIG. 7 is a bottom plan view thereof.

The broken lines in the figures are for illustrative purposes only and form no part of the claimed design.
